CLAIM

The design for a trash receptacle, substantially as shown and described.

DESCRIPTION

FIG. 1 is a front perspective view of a trash receptacle according to the invention.

FIG. 2 is a left side elevation view of a trash receptacle according to the invention.

FIG. 3 is a right side elevation view of a trash receptacle according to the invention.

FIG. 4 is a front elevation view of a trash receptacle according to the invention.

FIG. 5 is a rear elevation view of a trash receptacle according to the invention; and,

FIG. 6 is a top elevation view of a trash receptacle according to the invention.

The bottom view of the design forms no part of the claimed design. The broken line portions of the drawings, including the bars, the frames for advertising, the hinged frame enclosure, and the receptacle base, are environmental and do not form part of the claimed design.
